Feeder Nominated for High Tech Platform IIA, posted on vanberlo.nl, posted Feb. 3, 2017, no production date given, [online], [site visited May 10, 2018], Available from Internet, URL: <https://vanberlo.nl/en/news/70/uniqster-feeder-nominated-for-high-tech-platform-iiia> (Year: 2017).*

Primary Examiner — Melanie H Tung*Assistant Examiner* — Fitzgerald L Butac(74) *Attorney, Agent, or Firm* — Peretz Chesal & Hermann, P.L.(57) **CLAIM**

The ornamental design for a “filling machine for canister,” as shown and described.

DESCRIPTION

FIG. 1 is a top perspective view of a filling machine for canister;

FIG. 2 is a bottom perspective view thereof;

FIG. 3 is a top view thereof;

FIG. 4 is a bottom view thereof;

FIG. 5 is a side plan view thereof;

FIG. 6 is a front plan view thereof; and,

FIG. 7 is a back plan view thereof.

The broken lines show portions of a filling machine for canister that form no part of the claimed design.
